UNITED STATES PATENT OFFICE

WILHELM B. BRONANDER, OF MONTCLAIR, NEW JERSEY, ASSIGNOR TO AMERICAN MACHINE & FOUNDRY COMPANY, A CORPORATION OF NEW JERSEY

HOT AND COLD CIGARETTE ROD SEALER

Application filed April 30, 1930. Serial No. 448,667.

This invention relates to hot and cold cigarette rod sealers for continuous rod cigarette machines, such as are used for the purpose of sealing the freshly pasted seam 5 of the cigarette rod before it enters the cutoff by which it is cut into cigarette lengths.

When a continuous cigarette rod is sealed by a heated sealing unit at high linear speed it is noticeable that the seam is still 10 slightly moist on emerging from the sealer. This moisture on the paper of the cigarette rod causes trouble in the operation of the machine, especially at the point at which the cigarette rod enters the mouth-piece and ledger tube of the cutoff.

To overcome this trouble, which increases with the speed of the machine, the present improved sealer is provided with a heating unit which operates on the seam and squeezes 20 out and carries off the surplus paste and is also provided with one or more cold drying bars which cool off the paste and avoid sweating of the cigarette rod in the cutoff mechanism. In order to set the paste in the 25 seam and to dry the surplus taken off, the heating unit is made in the form of a rotary disk which turns with the advancing cigarette rod and heats the latter at the point of tangency only. The subsequent long contact of the cigarette rod with the cold sealing bars causes the condensation of all moisture, so that the rod is entirely dry when leaving the sealing unit and a smooth running of the machine is secured.

The main object of the present invention is, therefore, the production of a sealer for continuous rod cigarette machines which avoids the disadvantages of prior constructions pointed out above, by the provision of 35 cooling means together with heat applying means for operating on the seam of the cigarette rod. With these and other objects in view, the invention consists in certain constructions and combinations which will be hereinafter fully described and then specifically set forth in the claims hereunto appended.

In the accompanying drawings which 50 form a portion of this specification and in

which like characters of reference indicate the same or like parts:

Fig. 1 is a plan view of the improved sealer;

Fig. 2 is a front elevation of the same; 55 and

Fig. 3 is a side elevation taken on line 3-3 of Fig. 1.

In carrying the invention into effect, there is provided means for applying heat to the 60 freshly pasted travelling seam of a cigarette rod, and means for immediately thereafter applying pressure and cooling said seam. In the best constructions contemplated, the heat applying means includes a heated rotatable disk and the pressure applying and cooling means includes a plurality of cooling bars. In the best constructions contemplated, also, these means are supported in a frame moveable in and out of operative position. 65

Referring to the drawings, the entire sealing unit is mounted on a swingable frame or arm 5 mounted on a pivot 6 which is supported by the sealer bracket 7 fastened to the frame of the cigarette machine. The arm 5 carries a bracket 8 supporting a heat insulating disk 9, of asbestos or any other suitable material, to which is fastened the heat distributing disk 10 having imbedded 70 in it the electric heating unit 11. The arm 5 is provided with ball bearings 12 supporting the horizontal sealing disk shaft 13 which has an integral flange 14 supporting a heat insulating disk 15 to which is fastened the sealing disk 16, which is spaced from the heat distributing disk 10 to receive heat by radiation therefrom. Sealing disk 16 is frictionally driven from the continuously moving cigarette rod C. A hand wheel 17 is provided on the shaft 13 through which the sealing disk 16 may be turned by hand if desired. 85

The heating unit 11 receives electric current through wires 18 passing through connection box 19 mounted on arm 5. The latter furthermore carries the heat insulating plate 20 on which is mounted the first cooling bar 21 which is slotted at its forward end to clear the sealing disk 16 so as to per- 95 100

mit contact with the cigarette rod C close to its heating contact with the disk. The bar 21 is separated from a second sealing bar 22 to prevent its being heated by the latter 5 which is kept at a relatively higher temperature due to its proximity to the sealing disk and heat distributing disk, and the bar 22 is likewise mounted on arm 5, but without heat insulation, in order that it may distribute 10 the heat received by it from the seam to the frame, thereby maintaining a temperature lower than that of the seam.

In order to regulate the friction of the sealing disk 16 and of the cooling bars 21 15 and 22 on the continuously travelling cigarette rod C, arm 5 is provided with an adjusting screw 23 resting on lug 24 of the sealer bracket 7, which enables the operator to raise or lower the sealing unit. The adjusting screw 23 has a lock-spring 25. For conveniently performing a complete back-swing of the sealer, when the machine is stopped for any reason with a cigarette rod in place, a handle 26 is provided which is 25 fastened to arm 5.

In view of the foregoing, a detailed description of the operation of the machine is deemed to be unnecessary, and it is therefore omitted in the interest of brevity.

30 What is claimed is:

1. The combination with means for applying heat to the freshly pasted traveling seam of a cigarette rod, of mechanism for immediately thereafter applying pressure and cooling said seam, whereby sweating of the cigarette rod is avoided.

2. The combination with means for applying heat to the freshly pasted traveling seam of a cigarette rod, of mechanism for immediately thereafter applying pressure and cooling said seam, whereby sweating of the cigarette rod is avoided, said means including a heated wheel contacting said seam.

3. The combination with means for applying heat to the freshly pasted traveling seam of a cigarette rod, of mechanism for immediately thereafter applying pressure and cooling said seam, whereby sweating of the cigarette rod is avoided, said means including a heating wheel contacting with and rotated by said seam.

4. The combination with means for applying heat to the freshly pasted traveling seam of a cigarette rod, of mechanism for immediately thereafter applying pressure and cooling said seam, whereby sweating of the cigarette rod is avoided, said means including a wheel contacting with said seam, and an electrically heated member out of contact with but heating said wheel by radiation.

5. The combination with means for applying heat to the freshly pasted traveling seam of a cigarette rod, of mechanism for immediately thereafter applying pressure and

cooling said seam, whereby sweating of the cigarette rod is avoided, said mechanism including an unheated bar extending along said seam behind said heat applying means.

6. The combination with a frame movable in and out of operative position, of means supported in said frame for heating the pasted seam of a traveling cigarette rod, and mechanism supported by the frame for thereafter cooling the seam, whereby sweating of the cigarette rod is avoided.

7. The combination with a frame movable in and out of operative position, of means supported in said frame for heating the pasted seam of a traveling cigarette rod, and mechanism supported by the frame for thereafter cooling the seam, whereby sweating of the cigarette rod is avoided, said means including a heated disk rotatably mounted in said frame and contacting with the seam in the operative position of the frame and adapted to be rotated by the cigarette rod.

8. The combination with a frame movable in and out of operative position, of means supported in said frame for heating the pasted seam of a traveling cigarette rod, and mechanism supported by the frame for thereafter cooling the seam, whereby sweating of the cigarette rod is avoided, said means including a heated disk and a heating member therefor.

9. The combination with a frame movable in and out of operative position, of means supported in said frame for heating the pasted seam of a traveling cigarette rod, and mechanism supported by the frame for thereafter cooling the seam, whereby sweating of the cigarette rod is avoided, said mechanism including an insulated cooling bar disposed adjacent to the heating means and adapted to engage the seam and a non-insulated cooling bar remote from said heating means and adapted to engage the seam.

In testimony whereof, I have signed my name to this specification.

WILHELM B. BRONANDER.
